UNITED STATES PATENT OFFICE.

HERMAN KRAUTH, OF MERIDEN, CONNECTICUT.

DESIGN FOR A BOTTLE OR JAR.

SPECIFICATION forming part of Design No. 27,819, dated November 9, 1897.

Application filed August 19, 1897. Serial No. 648,835. Term of patent 7 years.

To all whom it may concern:

Be it known that I, HERMAN KRAUTH, of Meriden, county of New Haven, State of Connecticut, have invented and produced a new 5 and original Design for Necks and Handles for Bottles or Jars, of which the following is a specification, reference being had to the accompanying drawing, forming a part thereof.

The drawing shows a perspective view of 10 my newly-designed necks and handles for bottles, jars, &c.

The leading feature of my design consists in two bands or collars placed one above the other and connected by ornamental handles. 15 The upper band or collar consists of an open scrollwork portion *a*, made flaring at the upper end, a beaded band *a'* at the lower end thereof, and ornamental depending portions

*a*² below said beaded band *a'*. The lower band or collar consists of a plain band *c* and 20 below it ornamental open scrollwork *c'*. Scrollwork handles *d* connect said upper and lower bands or collars, said handles being beaded or otherwise ornamented.

I claim—

The design for necks and handles for bottles, jars, &c., substantially as herein shown and described.

In testimony whereof I have signed my name to this specification in the presence of 30 two subscribing witnesses.

HERMAN KRAUTH.
